UNITED STATES PATENT OFFICE.

CHARLES A. MYERS, OF SOUTH GREENFIELD, MISSOURI.

DRAFT DEVICE.

1,092,077.

Specification of Letters Patent. Patented Mar. 31, 1914.

Application filed May 20, 1913. Serial No. 768,782.

To all whom it may concern:

Be it known that I, CHARLES A. MYERS, a citizen of the United States, residing at South Greenfield, in the county of Dade and 5 State of Missouri, have invented new and useful Improvements in Draft Devices, of which the following is a specification.

This invention is an improved draft device here shown as a whiffletree provided at 10 the ends with improved means for attaching and releasing the traces and at the center with improved means for attaching the whiffletree to a doubletree or to the cross bar of a pair of thills or to anything or vehicle 15 to be drawn by the whiffletree, the invention consisting in the construction, combination and arrangement of devices hereinafter described and claimed.

In the accompanying drawing: Figure 1 20 is a perspective view, from the rear side, of a whiffletree constructed in accordance with my invention. Fig. 2 is a detail longitudinal horizontal sectional view of the same. Fig. 3 is a detail central transverse sectional 25 view of the same. Fig. 4 is a detail transverse sectional view of the same at a point near one end thereof.

The whiffletree 1 is U-shaped in cross section so that a channel 2 is formed in its rear 30 side which extends from end to end thereof. The whiffletree is, in practice, made preferably of plate iron, or steel, bent to form a channel bar. The front side of the whiffletree is straight, its rear side is angular longitudinally, the width of the whiffletree being greatest at its center and least at its 35 ends.

In the center of the whiffletree, in the channel thereof, is fitted a filler and brace 40 block 3, the upper and lower webs or walls of the whiffletree being secured to the block as by means of rivets or bolts 4 which pass through the webs of the whiffletree and also through the block.

An eye bolt 5 has its shank passed through 45 center alined openings in the front side of the whiffletree and the block 3, the eye 6 of the bolt being at the rear end and a nut 7 being threaded on the front end of the bolt 50 and bearing against the front side of the whiffletree. This eye bolt forms a means for attaching the whiffletree to the vehicle or other object to be drawn and also assists in securing the block 3 in the whiffletree and in 55 bracing and strengthening the construction

of the whiffletree in coaction with the said block.

In each end of the channel of the whiffletree is a filler, guide, and attaching block 8 which is secured in place by rivets or bolts 60 9 which pass through the webs of the whiffletree and also through the said blocks. These blocks are provided in their outer sides, near their outer ends with vertical transverse recesses 10 which are sufficiently large to receive the rear ends of traces and the whiffletree is also provided with similar recesses 11 with which the recesses 10 coincide. Each block 8 has a longitudinal bore 12, the outer end portion 13 of which is of greater diameter than the inner end portion 14.

An attaching bolt 15 is fitted for longitudinal movement in the larger portion 13 of each bore 12 and has a reduced stem 16 fitted for longitudinal movement in the 75 smaller portion 14 of each bore. On the stem of each bolt is a coiled extensile spring 17 which bears against the shoulder formed at the inner end of the enlarged portion of the bolt and also against the inner end of 80 the enlarged portion of the bore, the said springs acting to move the said bolts outwardly so as to cause said bolts to be projected and normally held in position across the recesses 10 which receive the rear ends 85 of the traces, the bolts being adapted to pass through the openings or cockeyes at the ends of the traces and, hence, serving to securely and yet detachably connect the traces to the ends of the whiffletree. Each block 8 also 90 has a longitudinal horizontal slot 18, in which operates a pin 19. The said pins are attached to the bolts 15 and are here shown as passing through openings with which the said bolts are provided. The pins project 95 rearwardly from the blocks and, hence, serve to enable the attaching bolts 15 to be readily moved inwardly against the tension of the spring 17 when it is desired to release the traces. The said pins also, by coacting with 100 the outer ends of the slots 18 limit the outward or locking movement of the bolts under the action of the spring 17. It will be observed that the blocks 8 in which the locking bolts, their actuating springs and operating pins are mounted are entirely contained in the ends of the channel of the 105 whiffletree so that there are no parts projecting. The blocks 8 in addition to forming the guides and housings for 110

the attaching bolts and their operating springs and pins also form fillers for the ends of the whiffletree and serve to greatly strengthen the construction of the 5 whiffletrees. It will be understood that the locking bolts are not liable to become causally detached from the traces and, hence, there is no danger of the traces becoming disconnected casually from the whiffletree ends.

10 I claim:—

A draft device of the class described having a longitudinal channel in its rear side extending from end to end thereof and provided near its ends in its front side with 15 recesses, filler blocks secured in the ends of the channel and having bolts wholly carried by and mounted for movement in the filler blocks and across the said recesses to engage and disengage the rear ends of traces placed

in said recesses, springs to normally hold the 20 attaching bolts in engaging position, the said springs being also mounted in and wholly carried by the filler blocks and operating pins for the attaching bolts movable therewith and also mounted for movement in the 25 filler blocks, said pins being secured to and extending rearwardly from the attaching bolts and the said filler blocks having longitudinal slots in which said pins operate, said slots and pins also limiting the extent of 30 longitudinal movement of the bolts.

In testimony whereof I affix my signature in presence of two witnesses.

CHARLES A. MYERS.
